(57) **CLAIM**

The ornamental design for a "tire," as shown and described.

DESCRIPTION

FIG. 1 is a perspective view of a tire of the present application taken from the front and a right side thereof; FIG. 2 is a front view of the tire shown in FIG. 1; FIG. 3 is a rear view of the tire shown in FIG. 1; FIG. 4 is a right side view of the tire shown in FIG. 1; FIG. 5 is a left side view of the tire shown in FIG. 1; FIG. 6 is a top view of the tire shown in FIG. 1; FIG. 7 is a bottom view of the tire shown in FIG. 1; and, FIG. 8 is an enlarged front elevation view of FIG. 2, showing a portion thereof.

The broken line showing of a tire bead is for the purpose of illustrating portions of the tire and forms no part of the claimed design.
